PEGBOARD MOUNTED SUPPORT FOR A HEDGE TRIMMER

Albert J. Enckler, North Olmsted, Ohio, assignor to
A-B-L Associates, Inc., Cleveland, Ohio

Filed Sept. 11, 1975, Ser. No. 602,453

Term of patent 14 years

Int. Cl. D6—04

U.S. Cl. D6—114

Fig. 1

Fig. 2

Fig. 3

FIG. 1 is a perspective view of a pegboard mounted support for a hedge trimmer showing my new design;

FIG. 2 is a side elevational view thereof; and

FIG. 3 is a front elevational view thereof.

I claim:

The ornamental design for a pegboard mounted support for a hedge trimmer, as shown and described.
